UNITED STATES PATENT OFFICE.

JESSE EVERETT ESHBAUGH, OF FLINT, MICHIGAN, ASSIGNOR TO A C SPARK PLUG COMPANY, OF FLINT, MICHIGAN, A COMPANY OF MICHIGAN.

HEAT INDICATOR.

Application filed January 31, 1927. Serial No. 164,848.

This invention relates to heat indicators for use on internal combustion engines, particularly engines used on motor vehicles.

In my invention I make use of certain paint substances which have the well known property of changing their color when heat above a certain temperature is applied thereto. I make use of a surface to which a coating of such paint is applied, this surface being the exposed end of a metal rod, the other end of which preferably extends into the air space above the water in the upper tank of the radiator although it may dip down into the water. Preferably the rod is arranged to extend through the radiator cap and at its line of connection with the cap is equipped with a bushing of heat insulating material to prevent the escape of heat.

My heat indicator is preferably provided with a top plate having a concave surface to the rear of the painted surface of the rod which extends through the lower portion and up into the upper portion of the plate across the concave surface leaving the intermediate portion of the rod free and exposed to view. The concavity serves as a reflecting surface rendering greater visibility to the color change of the painted surface.

The heat produced by the rising temperature of the water is conducted by the lower end of the metal rod to the exposed painted part and when the temperature rises sufficiently high it will cause a change in the color of the paint, thus indicating to the driver that the danger point has been reached.

The invention is illustrated in the accompanying drawing in which:

Figure 1 is a sectional view looking from the rear showing the device applied to the radiator cap of an automotive vehicle.

Figure 2 is a section on the line 2—2 of Figure 1.

Referring to Figure 1, 1 indicates the radiator shell and 2 the upper radiator tank having an outturned annular flange 3 to which is secured the externally threaded collar 4 and onto which is screwed a radiator cap 5. This cap has a threaded opening 6 for the reception of the threaded extension 7 of the top mounting plate 8. The extension 7 is retained on the cap by means of a washer 9 and nut 10 threaded onto the end 7 which projects through the radiator cap. The plate 8 is rectangular in form and has

a concave reflecting surface 11 and an opening 12 at its upper marginal portion. The end 7 has a bore 13 in which is received a heat insulating bushing 14 through which passes a metal rod 15, preferably of copper, the upper end 16 of which projects into opening 12. It will be noted that the opening 12 is slightly larger than the end 16 to prevent any contact between the rod and the plate or the end 16 may be hexagonal so that any contact will be on a line. The lower end of the rod 15 terminates in the air space of the tank 2, but it may obviously extend down into the water, or may be replaced by a tube.

The concaved surface 11 is recessed as at 17 so that it may be free of the surface 18 painted on the upper portion of the rod 15 as suggested hereinbefore.

The operation of my device is as follows: Heat from the vapor of the water in the tank 2 or from the water itself is transmitted from the lower portion of the rod 15 to the upper painted portion 18 and when a sufficiently high degree of the temperature has been reached, the painted surface will change from its normal color which may be considered as yellow, to a different color, for example, a bright red. The reflecting surface in back of the painted end 18 will reflect and intensify the color change, thereby insuring greater visibility and rendering more pronounced the change in the heat condition within the radiator. As the vapor cools, the color change will reverse.

I claim:

1. A heat indicator for internal combustion engines of motor vehicles, a radiator cap, a metal rod extending through an opening in said cap, an upper plate portion having a concave surface associated with said rod to act as a reflector, an extension on said plate secured in said cap, a heat insulating bushing in a bore in said extension and surrounding said rod, a coating of heat sensitive paint at the upper end of said rod, and a groove in said plate, said coated surface extending parallel to said groove.

2. In a heat indicator, a member adapted to transmit heat from a body the temperature of which is to be indicated, means inter-related with said member to indicate heat changes, and a framed reflector inter-related with said member, said member extending entirely across the reflecting sur-

face and passing through one edge of the reflector frame and extending into the second edge.

3. The invention of claim 2, said member being free of contact with said second edge.

4. The invention of claim 2, said reflecting surface having a curved outline.

5. In a heat indicator, a member adapted to transmit heat from a body the temperature of which is to be indicated, means associated with said member to indicate heat changes, a mounting for said indicator, and an insulating bushing between said member and mounting.

6. In a heat indicator, a rod to transmit heat from a body the temperature of which is to be indicated, a support for said rod, a rectangular frame attached to said support, a curved reflector in the rectangle of said frame at one side of said rod, and means on said rod to indicate temperature changes.

7. The structure of claim 6, said means comprising a coating of heat sensitive paint and said reflector having a central groove in the rear of said coating of paint.

In testimony whereof I affix my signature.

JESSE EVERETT ESHBAUGH.
